UNITED STATES PATENT OFFICE.

GEORGES LOUIS OLIVIER BÉNARD, OF BLOIS, FRANCE.

METHOD OF AND APPARATUS FOR DETERMINING THE SHAPES OF AIRPLANE PARTS.

Application filed December 19, 1925, Serial No. 76,523, and in France December 19, 1924.

Airplane constructors endeavour to give to their machines always greater speeds either by devising more powerful motors or by modifying the shaping of the wings, 5 shells, cross-ties, in a word of all the constructional parts of the machines.

Shapes of wings and of shells are constantly being altered and such alterations result from investigations conducted to determine 10 the drag of the various parts through air. Dynamometer readings taken from reduced models stationary in tunnels do, indeed, show said drag, but afford no accurate indications as to what alterations should be introduced in order to obtain minimum drag 15 at a given speed.

The object of my invention is to provide a process permitting to determine in advance, by means of laboratory experiments simple, prompt, and inexpensive, what shapes should best be given to constituent 20 parts of an airplane for defined speeds of, say, 150, 200, 250 or 300 kilometers per hour.

My process consists in coating a reduced model of the airplane with a greasy material, solid but fusible at a temperature readily obtained in practice. Said reduced model, so coated with greasy material, is then exposed to a current of air heated up to the temperature equal to the melting 30 point of the greasy material. Under such conditions, the greasy material will be melted or peeled off the quicker and the more thoroughly where the drag is greater, and, according to the location and degree of wear 35 shown by the tested pieces, it can then be ascertained what alterations should be made in the prime model to minimize drag at any given speed.

My process will also permit accurately to determine eddies, their importance, reciprocal reactions on the wings of several-decked planes, etc., etc.

Again my process will allow the safety of machines to be increased by permitting investigation of possible alterations in the main parts, while reducing to a pre-admitted minimum the inconveniences or drawbacks involved by the modifications brought to the outer forms.

Lastly my process, as applied to the designing of propellers and of projectiles or of any other bodies moving through air, will afford to a certain extent valuable hints concerning how best they should be shaped.

The solid greasy materials that I would

propose to use may be; for instance, paraffine, stearine, spermaceti or such like, the melting points of which are over 36° C. to permit handling thereof and below 65° C. 60 a temperature up to which the air blast can easily be heated. The melting point of the material used should, preferably be somewhere between 45 and 65° C.

In order to make my invention more clearly understood I have illustrated, merely as an example, an embodiment thereof in and by a drawing appended hereto and wherein:

Figure 1 is a longitudinal section of my device.

Figure 2 is a plan view of the same.

Figure 3 is a cross section thereof.

In all the figures the same reference letters denote the same parts.

My device comprises essentially an open-ended metal or wooden cylinder *a* of a suitable size, preferably 2 meters in diameter and 4 meters long. It is located in the center of a chamber *b* about 8 meters long by 6 meters wide and 5 meters high; these 75 dimensions being, of course, given merely by way of example and subject to numerous alterations.

At one of the cylinder ends is positioned a powerful fan *c* and, behind said fan, a grate *d* intended to straighten the air currents produced by the fan. Within chamber *b* and, for instance, on either side of cylinder or tunnel *a* radiators *f* are fitted up.

The reduced models to be experimented with are suspended by any suitable means inside cylinder *a*, after having been, of course, coated with paraffine or such like material. I then raise the temperature in the chamber *b* until it reaches the melting point of the 95 greasy material used, and I cause the fan to be operated at such a speed as will impart to the air current or blast the desired velocity. I allow operation to go on for some moments, then stop the fan, cool the chamber and withdraw the model.

Where the blast has met with the greatest resistance, the greasy material will have been melted and blown off.

Where the blast has met with no resistance 105 the parts tested will have undergone no modification.

Inspection of the parts experimented with will show the kind and importance of the alterations to be introduced.

I claim as my invention:

1. In a method of determining the shapes

- of airplane parts, the steps of coating a reduced model of an airplane with a solid greasy substance having a low melting point; and blowing against the coated model, while in suspended position, a current of air heated to the melting point of the coating substance and traveling at the velocity in view of which the form or shape of the model is to be determined.
2. In a method of determining the shapes of airplane parts, the steps of coating a reduced model of an airplane with a solid greasy substance having a low melting point; suspending the coated model in an open-ended cylinder disposed within a closed chamber; and blowing through such cylinder, so as to impinge against the suspended model, a current of air heated to the melting point of the coating substance and traveling at the velocity in view of which the form or shape of the model is to be determined.
3. In a method of determining the shapes of airplane parts, the steps of coating a reduced model of an airplane with a solid greasy substance having a melting point between 45 and 65° C.; and blowing against

the suspended model a current of air heated to the melting point of the coating substance and traveling at the velocity in view of which the form or shape of the model is to be determined.

4. Apparatus for determining the shapes of airplane parts, comprising a closed chamber of large capacity; an open-ended cylinder supported in horizontal position in the center of the chamber, and from the top wall of which a reduced model of an airplane coated with a greasy substance is adapted to be suspended; a fan located at one end of the cylinder for blowing a current of air therethrough at the required velocity so as to impinge against the suspended model; and heating means for raising the temperature of the air current to the melting point of the coating substance.

5. Apparatus according to claim 4, in which a grate is disposed in the cylinder adjacent the end where the fan is located, to direct the streams of air in straight lines toward the model.

In testimony whereof I affix my signature.
GEORGES LOUIS OLIVIER BÉNARD.
